UNITED STATES PATENT OFFICE.

JOHN T. FAIRBAIRN, OF HYDEPARK, MASSACHUSETTS.

SELF-CLEANING SAFETY-TREAD.

SPECIFICATION forming part of Letters Patent No. 683,642, dated October 1, 1901.

Application filed December 13, 1900. Serial No. 39,730. (No model.)

To all whom it may concern:

Be it known that I, JOHN T. FAIRBAIRN, of Hydepark, in the county of Norfolk and State of Massachusetts, have invented certain new and useful Improvements in Self-Cleaning Safety-Treads, of which the following is a specification.

This invention relates to an improved self-cleaning safety-tread; and it consists in the novel features of construction and arrangement of parts hereinafter described and claimed.

Reference is to be had to the accompanying drawings, forming a part of this application, and to the figures of reference marked thereon, the same reference characters designating the same parts or features, as the case may be, wherever they occur.

Of the drawings, Figure 1 is a plan view of a sheet-metal blank, showing the lines upon which the metal part or holder of the tread is struck up. Fig. 2 is a perspective view of a pair of the units or holders. Fig. 3 is a like view of one of the holders. Fig. 4 is a cross-sectional view of a partially-completed tread, the same appearing as it would were it taken on the line 4 4 of Fig. 2 and if in that figure there were five treads instead of two and three of the channels or units contained no anti-friction-filler. Fig. 5 is a cross-sectional view of a partially-completed tread, the same appearing as if it were taken on the line 5 5 of Fig. 2 were only three of the chambers filled with lead. Fig. 6 is a top plan view of my improved self-cleaning safety-tread completed, showing one way in which several units may be combined.

My invention comprises a self-cleaning safety-tread made up of units separated by a bottomless clearance-channel, whereby the units may be combined in any desired shape and the resulting tread will have always the described series of units, with an unobstructed clearance-channel between each pair of units.

The unit of my improved tread is composed of a holder of sheet metal struck up to the required form, combined with a lead or other non-slipping filler united to and held by the holder. If more than one unit is to be employed, the several or required number of holders—two or more—may be struck up from

a blank simultaneously and connected at their ends or elsewhere by uncut portions of the blank.

1 represents a sheet-metal blank from which my holder is made.

In Fig. 1, 2 2 represent longitudinal cuts; 3 3, end cuts; 4 4 4, longitudinal lines upon which the flaps 5, that form the side walls or supports of the holder, are cut and bent to the positions shown in Fig. 2.

6 6 represent longitudinal cuts, 7 an end cut, and 8 the end line upon which the end walls or supports 9 are cut and bent to the 65 positions shown in Fig. 2. Preferably the end walls are cut away to form notches 10, in which the lead filler 11 may interlock, as shown in Fig. 4. (See also Fig. 1.) If but one holder is to be struck up at a time, the bottom wall 70 14 of the holder may be extended to form ears 15, by which the holder may be secured to the floor or step, &c. (See Fig. 3.) If more than one holder is struck up, they may be united by uncut side strips 16. (See Figs. 2 and 6.) 75 After the holder is formed as described pockets 70 are filled with lead 11 or other anti-slipping material in any desired way, the material 11 interlocking with the notches 10. The walls 5 and 9 serve to maintain the material 11 in place to prevent uneven wear of the latter and also serve as a scraper.

The units, as described, may be assembled in any preferred form, with some, at least, of the units separated to form open-bottom channels, into and through which dirt may fall to and upon the step, floor, or walk upon which the tread is placed.

The holder when in position serves not only, as stated, to prevent slipping and as a tread, 90 but also as a scraper, and dirt and other material fall through the channels, so that the tread is not an accumulator of dirt and other material, and the floor or step or walk upon which the tread is placed can be readily kept 95 clean by lifting the tread as one would a grid.

Having thus explained the nature of my invention and described a way of constructing and using the same, although without having attempted to set forth all the forms in which 100 it may be embodied or all the modes of its use, I declare that what I claim is—

1. As an article of manufacture, a self-cleaning safety-tread comprising a plurality

of chambered members having antislipping tread-surfaces, said members being separated to form open-bottom channels for the discharge of dirt, &c.

5. 2. A safety-tread comprising a sheet-metal form having side walls struck up to form a chamber, a plurality of walls subdividing said chamber, and a tread-surface of antislipping material arranged in said chamber and interlocked with its dividing-walls.

3. A holder for safety-treads, comprising a bottom wall 14, side walls 5, and division-walls 9 struck up to form a channel for holding an antislipping wear-surface.

In testimony whereof I have affixed my signature in presence of two witnesses.

JOHN T. FAIRBAIRN.
